UNITED STATES PATENT OFFICE.

SOREN CHRISTIAN REPHOLDT, OF OMAHA, NEBRASKA.

TRAFFIC SIGNAL-TOWER.

1,275,749.

Specification of Letters Patent. Patented Aug. 13, 1918.

Application filed September 2, 1916. Serial No. 118,282.

To all whom it may concern:

Be it known that I, SOREN CHRISTIAN REPHOLDT, a citizen of the United States of America, residing at Omaha, in the county of Douglas and State of Nebraska, have invented certain new and useful Improvements in Traffic Signal-Towers, of which the following is a specification.

This invention relates to new and useful 10 improvements in traffic signal tower.

The primary object of the invention is the provision of a signal tower especially adapted for street crossings provided with traffic signals readily operable by the crossing officer 15 positioned within the tower, provision being made for the display of orders at diametrically opposite sides of the tower viewable in the direction of the oncoming traffic.

A further object of the device is the provision of an elevated tower at street intersections for the accommodation of the traffic or crossing officer stationed thereat, a ready means being arranged whereby the officer may gain exit and entrance to the tower 25 while the latter is provided with telephonic communication with distantly positioned similar towers at other street corners.

A still further object is the provision of four suitably arranged crossing signals having illuminating devices, the signals being readily shiftable simultaneously by the officer in charge in accordance with the traffic regulations, readily discernible different audible alarms being automatically sounded for denoting which of the two through 35 courses at the street intersection is open for traffic.

In the drawings forming a part of this application and in which like reference characters refer to corresponding parts throughout the several views:

Figure 1 is a central vertical sectional view through the device, a portion thereof being shown in side elevation, parts being 45 broken away.

Fig. 2 is a transverse horizontal sectional view through the tower.

Fig. 3 is a vertical transverse sectional view through one of the signals, enlarged.

Fig. 4 is an enlarged detail longitudinal horizontal sectional view through the inner end portion thereof.

Fig. 5 is a perspective view of one of the signal boards detached.

Fig. 6 is a front elevation of the lower

portion of the mounting member of the device showing the elevator in its lowered position.

Fig. 7 is a transverse horizontal sectional view thereof.

Fig. 8 is a detail view of the retaining latch for the elevator.

Fig. 9 is a perspective view of the signal operating means, parts being broken away.

Fig. 10 is a detail sectional view through 65 the central portion thereof, parts being shown in side elevation.

Fig. 11 is a perspective view of the selective audible signal members upon the roof of the tower, and

Fig. 12 is a reduced perspective view illustrating the position of the device at the intersection of two street car lines at a corner crossing.

The present device broadly consists of a 75 substantially cubical tower 10 mounted upon the top of a tubular column or post 11 vertically arranged at street crossings which may be provided with separate street car lines 12 and 13 crossing each other perpendicularly, 80 the tracks 12 being represented in Fig. 12 of the drawings as the north and south tracks, while the tracks 13 represent the east and west tracks, it being understood that the traffic upon the said tracks as well as 85 the streets upon which they are positioned travels forwardly upon the right hand side of the street in the customary manner.

The tower 10 is provided with an entrance and exit opening or door 14 in the bottom 90 thereof at one side of the column 11, the latter being provided with outwardly converging spaced wings 15 having rounds 16 transversely carried thereby forming a ladder between the base 17 of the column and the 95 tower 10. An elevator platform 18 is provided with a notch 19 in its inner side adapted for slidably mounting the platform upon the wings 15 as best illustrated in Fig. 7 of the drawings, a counterbalancing weight 20 100 being positioned within the column 11 connected with the platform 18 by means of a suitable rope 21 passing behind the ladder rounds 16 and arranged over suitable pulleys 22 adjacent the top of the column. By this 105 arrangement it will be seen that the traffic officer may step upon the platform 18 and release the retaining latch 23 carried by the platform whereby the weight 20 will assist in the ascent of the platform and officer, the 110

latter pulling himself up by means of the rounds 16. The descent is readily made in a reverse manner, it being noted that the rounds 16 may be employed as an ordinary 5 ladder if desired, while pairs of anti-friction rollers 24 are carried by the bottom of the platform 18 and travel upon the wings 15.

Each of the four sides of the tower 10 is provided with two windows 25 having parting strips 26 therebetween, outwardly projecting elongated casings 27 being horizontally secured to each of the said strips as best illustrated in Fig. 2 of the drawings. The casings 27 have communication with 15 the interior of the tower 10 by means of slots 28 in the parting strips 26 adapted for the longitudinally sliding signal boards 29 arranged therein, spring-pressed roller members 30 being arranged within the casings 27 and bearing upon the said boards. The casings 27 are each provided with a substantially centrally arranged transparent portion or panel 31 against which the boards 29 slide, the said boards having suitable 25 signal words such as "Stop" and "Cross" as indicated at 32.

It being understood that the traffic moves only forwardly uniformly in opposite directions at the opposite sides of the tower 10, 30 the transparent panels 31 are arranged in the casings 27 upon opposite sides thereof and suitably positioned for viewing the signs upon the boards 29 from the direction of the oncoming traffic. This is best illustrated in Fig. 1 of the drawings, it being understood that the signals upon the other two sides of the tower 10, not therein shown, are similarly arranged, the words "Stop" and "Cross" being interchanged upon each 35 of the two pairs of signal boards whereby the said boards under the control of hereinafter described mechanism always position the word "Stop" viewable in the casings of one pair of signals while the word "Cross" always simultaneously appears 40 viewable in the other pair of signals.

An operating disk 33 is rotatably carried by a sleeve 34 secured to a vertical shaft 35 centrally arranged within the tower 10, 50 links 36 being pivotally connected between the disk 33 and the inner ends of the boards 29. A projecting handle 37 is carried by the disk 33 whereby the latter may be partially rotated when desired for retracting 55 the boards 29 inwardly of the tower 10 thereby bringing the outer words 32 upon the boards 29 viewable through the transparent panels 31, the handle 37 being then utilized for again projecting the boards by 60 returning the disk to its normal position as best illustrated in Fig. 2 of the drawings. A telephone 38 is positioned within the tower 10 for use by the officer in charge to communicate with the officer in any 65 distantly positioned tower 10 for such purposes

as giving notice to intercept a vehicle which is exceeding the speed limit. Slides 39 are provided upon the casings 27 for covering the panels 31 when the signals are not in use. Mirrors 40' are arranged adjacent two 70 corners of the tower 10 for assisting the officer in viewing the streets.

It is often desirable to give different audible signals for the course of travel which is open under permission of the officer such 75 as the crossing whistle commonly employed and two bells 40 and 41 are mounted upon the roof 42 of the tower 10 for this purpose. Flattened resilient metallic bars 43 are vertically secured upon the disk 33 in radial arrangement with their upper free ends having paths of travel in the planes of the depending free ends 44 of separate tappers 45 for the said bells, the tappers being pivotally mounted upon a yoke bracket 46 carried by the said tower roof, the members 44 projecting through slots 47 and 48 in the said roof. By referring to Fig. 11 of the drawings, it will be seen that the slot 48 is of greater length than the slot 47 allowing the operating bar 43 positioned adjacent thereto to engage and pass the member 44 for ringing the bell 41 in whichever direction the disk 33 is turned when operating the signal boards 29. The bell 41 will therefore ring whenever the signal words are shifted, but by reason of the short length of the slot 47 the bar 43 which engages the tapper portion 44 for the bell 40 will only ring the same when moving in one direction 100 as the bar 43 will pass thereover when moving in the opposite direction by reason of the flexibility of the said bar, the end 49 of the slot 47 at such times forming an abutment for the tapper end 44 restraining the tapper from swinging pivotally thereby preventing the bell 40 from ringing during the return movement of the disk 33 and the boards 29. The shifting of the boards 29 by the officer within the tower thereby arranges the proper set of signal words 32 at the opposite sides of the tower for notifying the approaching vehicles upon both of the intersecting streets as to which crossing is clear and which one is closed at that time, 115 the ringing of either a single or both of the bells 40 and 41 also denoting corresponding information for the drivers of vehicles in the streets adjacent the tower.

A serviceable traffic adjunct is provided 120 whereby accidental collisions will be avoided at the intersection of streets, the visible as well as the audible signals being positive in their operation under the manipulation of the officer in charge. The preferred embodiments of the invention are herein illustrated although it will be understood that minor changes may be made therein without departing from the spirit and scope of the invention as claimed. 130

What I claim as new is:—

1. In a traffic signal tower, the combination of a column, an inclosure supported upon the upper end of the column, casings radiating from the inclosure from all sides thereof, slides mounted in the casings and having opposite indicia near opposite ends, the casings having transparent portions adapted to disclose the indicia one at a time, the opposite indicia being arranged alternately on opposite ends of the slides in adjacent casings, a rotary member mounted in the inclosure, and connections between all of the slides and said rotary member, the rotary member being adapted to be turned in one direction for simultaneously shifting all of the slides for disclosing opposite indicia successively about the inclosure and to be turned in an opposite direction for disclosing the opposite indicia in reversed order.
2. In a traffic signal tower, the combination of a column, a tower mounted on the upper end of the column and having four sides adapted to be positioned to face in opposite directions of intersecting streets, each side of the tower having a pair of windows thereat divided by a parting strip, a hollow casing projecting outward from each parting strip and opening therethrough to the interior of the tower, each casing having a transparent panel in one side of less length than the casing and adapted to face toward oncoming traffic at said side of the tower, a slide in each casing provided with spaced indicia regulating the movements of the traffic and the slides in the opposed casings being similar with the intermediate slides having the indicia oppositely arranged thereon, and a central controlling member arranged in the tower and connected to all of said slides for simultaneously operating the same.
3. In a traffic signal for intersecting streets, the combination of a tower having a side facing each radiating street from the intersection, a signal at each side of the tower, and a common operating means connected to all of said signals for simultaneously operating oppositely disposed signals for directing traffic to proceed and for simultaneously operating other oppositely disposed signals for directing traffic to stop.
4. In a traffic signal for intersecting roadways, the combination of a support, an indicating element at each side of the support facing an adjacent radiating roadway, and operating means connected to all of the indicating elements for simultaneously operating the same to indicate by certain indicating elements for traffic to proceed and for indicating by certain other elements for traffic to stop.
5. In a traffic signal for intersecting roadways, the combination of a tower, signaling elements mounted on the sides of the tower and facing the radiating roadways, and operating means connected to all of the alternate elements for simultaneously operating the same and indicating to traffic to proceed and connected to all of the intermediate elements for simultaneously indicating to traffic to stop.
6. In a traffic signal for intersecting roadways, the combination of a tower adapted to be placed in the middle of the intersection, signaling elements mounted on the sides of the tower and facing the respective radiating roadways, and means within the tower connected to the alternate elements for operating the same and indicating to traffic to proceed, and connected to all of the intermediate elements for indicating to traffic to stop.
7. In a traffic signaling device for intersecting roadways, the combination of a tower, a shaft vertically mounted in the tower, a disk carried by the shaft to turn therewith, indicating elements movably mounted upon the sides of the tower and facing the radiating roadways, and links connecting the indicating elements to said disk for simultaneously moving the indicating elements when the disk is turned, to indicate by oppositely-disposed indicating elements for traffic to proceed and to indicate by other oppositely-disposed indicating elements for traffic to stop.

In testimony whereof I affix my signature.

SOREN CHRISTIAN REPSHOLDT.
